DEVICE FOR FEEDING AN ADDITIVE
TO A MELT

Günter Köpke, and Kurt Ulbricht, Oberhausen-Sterkrade, Germany, assignors to Gutehoffnungshütte Sterkrade Aktiengesellschaft, Oberhausen-Sterkrade, Germany

Application July 21, 1955, Serial No. 523,407

Claims priority, application Germany July 24, 1954

6 Claims. (Cl. 266—34)

This invention relates to a device for feeding a melt with an additive tending to form vapor when contacting said melt, more particularly for feeding magnesium into an iron melt.

Magnesium has proved particularly suitable as an additive to iron, particularly in the production of cast iron. The evaporation temperature of magnesium, however, is considerably lower than the melting temperature of iron so that the magnesium tends to evaporate in the form of an explosion when it contacts the iron melt and thus causes a violent agitation of the melt.

Numerous suggestions have been made to prevent the evaporation of the magnesium in the form of an explosion as it enters the bath. It has been found essential to introduce the magnesium as deeply as possible below the bath level. The higher the static pressure of liquid iron above the point where the magnesium is introduced the more strongly will the evaporation of the magnesium be suppressed.

For this reason the magnesium has been introduced into the bath in most cases only after the ladle had been completely filled with the melt. This required the use of relative large melts. In the case of fluctuations in the manufacturing program, however, there may be cases where only small quantities of iron are to be treated at a time.

Besides, for the sake of uninterrupted operation, the treatment of cast iron should take place immediately after it has been tapped from the cupola. Previously the treatment had to be suspended until the iron tapped from the cupola had filled a ladle. The filling of a large ladle, however, takes a considerable period of time, during which the operation is interrupted and the temperature of the iron melt is reduced. That temperature drop is continued during the subsequent treatment of the melt with magnesium. As a result the spherulitic iron obtained by the treatment may be too viscous to be poured.

It is desired, therefore, to begin the feeding of the magnesium only a short time after the charging of the ladle with iron has begun, in order to utilize the charging time also for the treatment itself and thus to avoid an excessive cooling of the melt until it is poured. At the same time the feeding of the magnesium must be performed in such a manner that the evaporation of the magnesium will not cause an excessive agitation of the bath even in the early phase of the charging operation, when the iron has only a low static pressure.

It is an object of the invention to provide a device for suppressing the agitation caused in a melt when fed at or near its surface with an additive tending to form vapor when contacting said melt.

2

It is another object of the invention to provide a device for feeding a melt with an additive tending to form vapor when contacting said melt, which device permits of beginning the feeding of said additive into a melt vessel only partly filled with said melt without causing undue agitation of the latter.

It is another object of the invention to provide a device for feeding a melt with an additive tending to form vapor when contacting said melt, which device permits of feeding said additive to said melt during a major portion of the period in which said melt is being charged into a melt vessel.

It is another object of the invention to provide a device for feeding a melt with an additive tending to form vapor when contacting said melt, which device substantially avoids an introduction of said additive into said melt in other than vaporous form.

With these and other objects in mind, which will become apparent as the specification proceeds, the invention provides a device for feeding an additive into a melt, comprising a chamber member having a closed top and a side wall, a partition dividing the interior of said chamber member into a feed chamber and a vapor escape chamber, said chambers being open at their lower end and communicating with each other at the top of said chamber member, said partition extending downwardly beyond the lower end of said side wall, and inlet means arranged to feed said additive directly to said feed chamber.

Two illustrative embodiments of the invention are shown diagrammatically in the drawing.

The overall arrangement shown in both figures comprises a melting furnace 1 for the iron to be treated and a ladle 4 movable by means of a car 3 and adapted to be charged through the spout 2 of the furnace 1.

According to Fig. 1 the feeding device of the invention comprises a chamber member 6 having a closed top and a refractory-lined annular cylindrical side wall, which is slightly immersed in the iron bath 7 in the ladle. An annular cylindrical partition 8, which is concentric with the side wall of the chamber member 6, divides the interior of the member 6 into a feed chamber and a vapor escape chamber. Both said chambers are open at their lower end. The partition 8 extends downwardly into the iron bath beyond the lower end of the side wall of the chamber member 6. The upper end of the partition 8 does not extend as far as to the top of the chamber member 6 so that the feed chamber and the vapor escape chamber communicate with each other at the top of the chamber member 6. The partition 8 is connected to the chamber member 6 by suitable means (not shown).

Inlet means are provided to feed the magnesium or another additive directly to the feed chamber. According to Fig. 1 said inlet means comprises a vertical feed tube 5, whose lower end is disposed on the vertical center line of and carries the chamber member 6 and opens into the interior of said chamber member directly above the feed chamber. The tube 5 is vertically adjustable relative to the ladle 4.

When the level of the iron melt has reached the lower rim of the partition 8 during the charging of the ladle 4, the magnesium or another additive, preferably in liquid form, is fed under pressure at a controlled rate through the tube 5 from above into the ladle. The magnesium will begin to evaporate immediately as it contacts the melt in the feed chamber. The vapor collecting in the feed

chamber is unable to rise into the tube 5 against the pressure of the inflowing liquid magnesium and passes over at the top of the chamber member 6 into the vapor escape chamber, in which it is downwardly deflected by the side wall of the chamber member 6 and can escape at this time between the lower rim of the side wall and the bath level. This escaping magnesium reacts to some extent with the liquid iron on the surface of the bath. The proper feeding of the additive can be checked without appreciable loss or other undesired results because it is indicated by the freely escaping, flame-forming magnesium vapor.

Shortly thereafter the bath level reaches the lower rim of the side wall of the chamber member 6 so that the lower end of the chamber member is entirely closed. The magnesium vapor must now penetrate the melt. It escapes from the chamber member again at the lower rim of its side wall because the static pressure to be overcome is lower there than at the lower rim of the partition 8 (cf. the arrows in Fig. 1). As the treatment is continued the reaction conditions, which are apparent from the bubbling on the bath surface, may be controlled by varying the feed pressure of the magnesium and/or the height of the feed tube in adaptation to the rising bath level, which would cause an increase in the static pressure if the feed tube were maintained at the same height.

According to Fig. 2 the feeding device of the invention is firmly incorporated in the ladle or melt vessel 4. It comprises again a chamber member 10, which has a closed top and a side wall, both of which are carried by and sealed to the lower part of the peripheral wall of the ladle 4. Thus the interior of the chamber member 10 is partly confined by a portion of the peripheral wall of the ladle 4. A partition 11 is provided, which divides the interior of the chamber member 10 into a feed chamber adjoining the peripheral wall of the ladle 6 and a vapor escape chamber. Both said chambers are again open at their lower end. The partition 11 extends downwardly beyond the lower end of the side wall of the chamber member 10. The upper end of the partition 8 does not extend as far as to the top of the chamber member 10 so that the feed chamber and vapor escape chamber communicate with each other at the top of the chamber member 10. The partition 11 may be connected to the peripheral wall of the ladle 4 or to the chamber member 10 by suitable means (not shown).

According to Fig. 2 the inlet means for feeding the additive directly to the feed chamber comprise a tube 9, which extends through the peripheral wall of the ladle 4 where it adjoins the feed chamber and opens into the latter.

The feeding of the magnesium or other additive begins again when the level of the iron melt has reached the lower rim of the partition 11 as the ladle is being charged. At this time the magnesium vapor formed may expand and escape below the side wall, which is not yet immersed in the melt. When the bath level has risen sufficiently to close the lower end of the chamber member 11 entirely, the agitation of the bath will be suppressed by the static pressure of the bath at the point where the vapor escapes. In this embodiment a control is possible only by a variation of the feed pressure of the magnesium.

The device according to the invention enables the magnesium to be fed at an early phase of the charging of the ladle already and ensures that the additive is utilized in a high degree and favorable manner for the treatment of the iron melt. In this connection it is important that the portion of the bath surface which is particularly highly agitated by the evaporation of the magnesium is contained in the closed-topped chamber member and the magnesium escapes in the form of vapor from the chamber member into the bath.

What is claimed is:

1. A device for feeding an additive into a melt, comprising a chamber member having a closed top and a side wall, a partition dividing the interior of said chamber

member into a feed chamber and a vapor escape chamber, said chambers being open at their lower end and communicating with each other at the top of said chamber member, said partition extending downwardly beyond the lower end of said side wall, and inlet means in direct communication with said feed chamber.

2. A device for feeding an additive into a melt, comprising a chamber member having a closed top and a side wall, a partition dividing the interior of said chamber member into a feed chamber and a vapor escape chamber, said chambers being open at their lower end and communicating with each other at the top of said chamber member, said partition extending downwardly beyond the lower end of said side wall, and inlet means comprising a feed tube having a lower end carrying said chamber member and opening into the interior of said chamber member directly above said feed chamber to feed said additive directly thereto.

3. A device for feeding an additive into a melt, comprising a chamber member having a closed top and an annular side wall, an annular partition which is concentric with said side wall and divides the interior of said chamber member into a feed chamber and a vapor escape chamber, said chambers being open at their lower end and communicating with each other at the top of said chamber member, said partition extending downwardly beyond the lower end of said side wall, and inlet means comprising a feed tube having a lower end carrying said chamber member directly above said feed chamber to feed said additive directly thereto.

25 4. A device for feeding an additive into a melt, comprising a chamber member having a closed top and an annular side wall, an annular partition which is concentric with said side wall and divides the interior of said chamber member into a feed chamber and a vapor escape chamber, said chambers being open at their lower end and communicating with each other at the top of said chamber member, said partition extending downwardly beyond the lower end of said side wall, and inlet means comprising a feed tube having a lower end carrying said chamber member directly above said feed chamber to feed said additive directly thereto, said lower end of said tube being disposed on the vertical center line of said chamber member.

30 5. A device for feeding an additive into a melt contained in a melt vessel formed with a peripheral wall, said device comprising a chamber member having a closed top and a side wall both of which are laterally sealed to the inside of the lower part of said peripheral wall, a partition dividing the interior of said chamber member into a feed chamber adjoining said peripheral wall and a vapor escape chamber, said chambers being open at their lower ends and communicating with each other at the top of said chamber member, said partition extending downwardly beyond the lower end of said side wall, and inlet means extending through said peripheral wall where it adjoins said feed chamber and opening into said feed chamber to feed said additive directly thereto.

35 6. A device for feeding an additive into a melt, comprising a chamber member having a closed top and a side wall, a partition dividing the interior of said chamber member into a feed chamber and a vapor escape chamber, said chambers being open at their lower end and communicating with each other at the top of said chamber member, said partition extending downwardly beyond the lower end of said side wall, inlet means in direct communication with said feed chamber, and means operatively associated with said chamber member for raising and lowering the same relative to the liquid level of the melt.

40 7. In an arrangement of the character described, in combination, first conduit means having a spout portion adapted to be immersed into a liquid to be treated, said spout portion being so constructed and arranged that a liquid treating medium flowing through said first conduit means into the liquid to be treated traverses but a portion of the cross-section of said spout portion; and second conduit means having one end portion in communication with the remainder of the cross-section of said spout portion of said first conduit means, said second conduit means being so constructed and arranged that its other end portion projects just below the surface of the liquid to be treated when said spout portion of said first conduit means is immersed therein, whereby when said spout portion of said first conduit means is immersed in a first metal in liquid state and said other end portion of said second conduit means projects below the surface of the liquid first

metal and when a stream of second metal having a boiling point substantially lower than the melting point of the first metal is passed in liquid state through said first conduit means, said stream flows through but said portion of the cross-section of said spout portion and is vaporized upon contact with said liquid first metal, whereupon the thus-vaporized second metal flows through said remainder of the cross-section of said spout portion and through said second conduit means so as to be introduced into said first liquid metal just below the surface thereof.
